[57] ABSTRACT

This disclosure includes embodiments of apparatus for generating patterns of pulses comprising fixed or random series of pulses of predetermined bit lengths using a first register driven by pulses at the pattern clock rate, and the stages of the first register being coupled each to drive at least one other register having multiple output stages, and the latter being coupled to gating means to be gated with outputs from said first register. Random series of pulse patterns are generated in an embodiment including switching of the outputs of the other registers to the gating means, which switching is controlled by random signals generated in another register.

FIG. 6

WORD GENERATING APPARATUS

This invention relates to a binary word generating apparatus for producing patterns of pulses.

For example, in the testing of PCM communication apparatus or the inspection of an integrated circuit, patterns of pulses of very high speed and long bit lengths are required. In order to obtain such patterns of pulses, there has already been used an apparatus wherein as many registers are used as bits as required and these registers are ring-connected to control switches connected to the respective register outputs to be closed or opened depending on whether the respective bits of the generated pulse pattern are high or low and output signals there pass through the switches and are combined and sent out. However, such apparatus, as many high speed operating registers as there are bits in the pattern and all register outputs must be combined by high resolution circuits. Therefore, in order to obtain patterns of pulses of high speed and long bit length the apparatus is very expensive and it is also difficult to make long bit lengths even using driving inputs having 25 to 50 bits at a rate of 200 MHZ.

Therefore, an object of the present invention is to cheaply provide a pattern pulse generating apparatus of high speed and having, for example, more than 1,000 bits.

Another object of the present invention is to cheaply provide a random pulse generating apparatus while at the same time reducing the number of registers requiring high speed operation.

In the accompanying drawings:

FIG. 1 is a view showing an embodiment of the apparatus of the present invention;

FIG. 2 is a wave form diagram for the respective parts in the apparatus shown in FIG. 1;

FIGS. 3 and 4 are respectively views showing other embodiments of the present invention;

FIG. 5 is a view showing an embodiment of the random pulse generating apparatus using the apparatus according to the present invention;

FIG. 6 is a view showing details of a part of the apparatus shown in FIG. 5.

The present invention shall be explained with reference to the drawings. FIG. 1 is an embodiment of the present invention wherein five flipflop circuits or registers 1₁, 2₁, — are connected in a ring to form a ring counter or feedback register and are driven with the output of a pulse generator O having a frequency equal to the clock frequency of the pulse pattern to be obtained. The respective outputs of the ring counter register F₀ comprising the initial stage, drive other ring counter registers F₁, F₂. Switches 1, 6, 11, —; 2, 7, 12, — are connected respectively to the outputs of the registers 1₁₂, 2₁₂ —; 1₂₂, 2₂₂, and the outputs obtained through the respective switches are applied respectively to OR-gate circuits G₀₁, G₀₂, —. In turn, their outputs and the outputs of the registers 5₁, 1₁, 2₁, — are applied to AND-gate circuits G₁, G₂, —. The outputs of these respective AND-gate circuits G₁, G₂, — are applied to an OR-gate G₀ through wave shaping circuits H₁, H₂, —, and the combined output is sent out of a terminal P.

Thus, in the apparatus in FIG. 1, the respective outputs of the ring counter flipflops 1₁, 2₁, — drive a plurality of other ring counter registers F₁, F₂, —. In turn, the outputs of the respective registers 1₁₂, 2₁₂, —; 1₂₂, 2₂₂, — are selectively applied to the output terminal P through the switches 1, 6 —, 2, 7, —, for example, the output of the register F₁ driven by the register flipflop 1₁ is gated with the output of the flipflop 5₁ which is one before the above mentioned flipflop 1₁ as the ring counter F₀ in the initial stage is driven by clock pulses. Therefore, if the output pulses of the pulse generator O are represented by a in FIG. 2, the flipflops 1₁, 2₁, —, 5₁ send out the outputs of b₁, b₂, —, b₅ in the diagram, respectively.

Further, the respective flipflops in the register F₁ send out the outputs of C₁, C₂, —, C₅ in FIG. 2 and those in the register F₂ send out the outputs of d₁, d₂, —. These outputs are applied to the switches 1, 6, —, 2, 7 —. However, since the switches 1, 6 and 16 are closed, but the switches 11, 21, 2 and

7 are opened, only the hatched pulses in FIG. 2 are applied to the AND-gate circuits G₁ and G₂ and the other pulses are cut off. Further, since certain outputs of the register F₀ are added to the AND-gate circuits G₁, G₂, —, in the diagram, only the

5 double hatched pulse portions pass through the above mentioned gate circuits and are sent out of the output terminal P as pulses of half the width through shaping circuits H₁, H₂, —. An e in FIG. 2 shows an output pulse train thus obtained. That is to say, pulses of a fixed width t are applied in the order of the numerals 1, 2, 3, — to the above described switches, the pulses having been passed through the AND-gate by certain outputs of the register F₀ and the output is shaped and is sent out of the output terminal. Therefore, if the respective switches 1, 2, 3, — are kept closed or opened depending on whether the respective bits of the pulse pattern to be obtained are high or low, a resulting pattern of pulses as in e in FIG. 2 is obtained. The numerals of the corresponding switches are shown above them. In the apparatus in the above mentioned FIG. 1, for example, to the gate circuit G₁ are applied the outputs of the register F₁ and the output of the flipflop 5₁ which is one stage before the flipflop 1₁ driving the register F₁. Therefore, as shown in C₁ and b₅ in FIG. 2, the output pulse of the flipflop 5₁ is applied to the trailing edge of the output pulses of

10 the OR-gate circuit G₀₁. Therefore, even in case a considerable lag is caused to the generating of signals by the register F₁ and OR-gate circuit G₀₁, there is no danger of a resulting lag between the two pulses applied to the AND-gate circuit G₁ or the others, and the operation is positive.

15 FIG. 3 shows an apparatus wherein any desired pattern of pulses can be obtained by using fewer registers than there are bits in the pattern. The same parts as in FIG. 1 are designated by the same corresponding numerals. That is to say, the register F₁₀ in which, for example, 40 stages are ring connected

20 is driven by the output of any one stage in the registers F₁, F₂, —. The outputs of the registers F₁ and F₁₀ are respectively combined and are applied to 200 AND-gate circuits A₁₁, A₂₁ —; A₁₂, A₂₂ — and similar switches S as in the apparatus in FIG. 1. Therefore, through five switches are connected to the register group F₁ in the apparatus in FIG. 1, they are increased to 200 switches in FIG. 3 which are 40 times as many and thus a pulse pattern of 1,000 bit positions in all can be obtained. And yet, the number of the flipflops is 40 × 5 + 5 × 5 + 5 = 230 and is reduced to be about one-fifth the number required in the case by a conventional system.

25 Further, in the apparatus in FIGS. 1 and 3, the registers F₁, F₂, —, F₅ are driven by the respective outputs of the register F₀ which is in turn driven with the output of the clock pulse generator O and the outputs of the respective stages of the registers are applied to the selecting switch. Therefore, in the apparatus in FIG. 1, as in e in FIG. 2, a pulse pattern of 25 bit positions is obtained. But, in the apparatus in FIG. 4, the registers F₁₁, F₁₂, —; F₂₁, F₂₂, —, — are driven respectively with the respective outputs of the registers F₁, F₂, —, F₅. Thus, when a plurality of stages of registers are driven sequentially and a selecting switch is connected to the register at the end, even a pattern pulse of more than 1,000 bit position at a high speed can be easily obtained. Also, in this apparatus, the width of the pulses applied from the register F₁₁, F₁₂, etc. to the AND-gate circuits corresponding to the gate circuit G₁, etc. in FIG. 1 or 3 is very large and pulses are delivered from the register F₀ on its trailing edge. That is to say, the lag of signals by the registers F₁, F₁₁, etc. can be expected to be large enough. Therefore, though more registers than in the apparatus in FIG. 3 are required, pattern pulses of a very high speed can be obtained.

30 As described above, in the present invention, the respective outputs from the ring-connected first register drive, a plurality of other ring connected registers and, as required, outputs from the stages of these registers are switched by selecting switch means controlled by the last register. Therefore, the first register operates at the clock frequency but the operating speeds of the registers in the second and third stages reduce in turn to 1/m, (1m:n), — wherein m and n represent the

number of stages in these registers. Therefore, the number of the registers requiring high speed operation is very small and most of the registers can be made low in resolution and cheap. Further, as no high performance is required, the apparatus can be made small by utilizing integrated circuits. As the flipflops driven directly with the output of the clock pulse generator are only those belonging to the first register patterns of pulses of many more bits than 1,000 can be easily obtained with a low power pulse generator. Thus, in the present invention, high speed and long bit lengths can be easily generated requiring only a few high speed registers, and the apparatus can be manufactured very cheaply. Most of the apparatus requires no high performance parts and therefore can be made small by utilizing integrated circuits. By the way, the above explanation has been made on the assumption that fixed pulse patterns are obtained by keeping the on-and off-states of the switch groups always constant. However, if the above mentioned switches are formed of electronic circuits and are respectively controlled in response to binary parallel signals the pulse pattern can be varied at a high speed. That is to say, such apparatus can be used also in the case of converting binary parallel signals to series signals.

The apparatus according to the present invention can be utilized also for an apparatus for generating pseudo random pulses of a maximum period to period sequence, that is, an M sequence.

In such apparatus, an adder having modulus 2 is inserted as a stage in one of the shift registers and, for example, the input and output of the preceding register are applied to take random pulses out of that register. However, as all of the many annularly connected registers are driven with clock pulses, in order to obtain high speed pulses, very many high speed operating registers are required so that the apparatus is very expensive.

According to the present invention, an apparatus providing high speed operation can be obtained cheaply.

FIGS. 5 and 6 show an embodiment of the present apparatus. The register R_0 in the initial stage and the other ring connected registers R_1 , R_2 and R_3 are respectively the same as the registers F_0 , $\dots$, F_5 shown in FIGS. 1, 3 and 4. The stages a_1, d_1, g_1 , $\dots$, b_1, e_1 , $\dots$, c_1, f_1 of the respective stages groups are respectively the same as the registers $1_{12}, 2_{12}$, $\dots$, $1_{22}, 2_{22}$ shown in FIGS. 1, 3 and 4 and their operations are also the same as in the apparatus shown in the above mentioned FIGS. 1 to 4.

The outputs of the stages a_1, d_1, g_1 , $\dots$, b_1, e_1 , $\dots$, c_1, f_1 of the respective registers R_1 , R_2 and R_3 and the output of a controlling register R_4 are applied to AND-gates Aa, Ad, Ag , $\dots$, Ab, Ae , $\dots$, Ac, Af . Further, the outputs of the above mentioned three sets of AND-gates are combined respectively at the OR-gates G_{01}, G_{02} and G_{03} and are further applied to the AND-gates G_1, G_2 and G_3 together with the outputs of the respective OR-gates and the outputs of the three flipflops stages A, B and C, and these outputs are combined at the OR-gate G_0 so that an M sequences random pulse train may be sent out of the output terminal P.

FIG. 6 is a detail view of the controlling register R_4 . Stages a_2, b_2, c_2 , $\dots$, 0_2 and adders Sa, Sb, Sc , $\dots$, So having modulus 2 are provided. A signal corresponding to the sum of its own output signal, and for example, the output signal of the flipflop in the preceding stage in FIG. 6 is applied to each flipflop and the output signal of the adder Sa is added through a memory stage M to the adder So provided at the input end of the stage 0_2 . Further, the output of the flipflop h_1 in FIG. 5 is applied from the terminal h_4 to the stages a_2, b_2 , $\dots$, g_2 to drive them. The output of the flipflop a_1 in FIG. 5 is applied from the terminal a_4 to drive the flipflops h_2, i_2 , $\dots$, 0_2 and M. Such output signals of the stage registers a_2, b_2 , $\dots$, 0_2 are respectively applied from the terminals a_3, b_3 , $\dots$, 0_3 to the AND-gates A_a, A_b , $\dots$, A_c , $\dots$, A_6 in FIG. 5.

In the described apparatus, the ring connected first register R_0 is driven by clock pulses at the terminal O and therefore operates at a high speed, but the succeeding ring connected registers R_1, R_2 and R_3 are only advanced by one step when-

ever the register R_0 completes one count or cycle and therefore their operating speed is reduced by one-third. Further, as the registers R_1, R_2 and R_3 are driven in turn in this manner, the respective registers operate in the sequence a_1, b_1, c_1 , $\dots$,

5 $0_1, a_1$, $\dots$ and send out output signals of a width three times as large as the clock pulse interval. Further, the controlling register in FIG. 6 is driven by the output of the ring connected register in the succeeding stage. Therefore, whenever the output delivered by the stages a_1, b_1 , $\dots$, 0_1 completes one round, or cycle one signal is sent out of each of the terminals a_3, b_3 , $\dots$, 0_3 . The AND-gates A_a, A_b , $\dots$ gate the outputs of the stages a_1, b_1 , $\dots$ to deliver "1" or "0" signals. Further, as the controlling stages a_2, b_2 , $\dots$, g_2 are driven by the output of the stage h_1 and the controlling stages h_2, i_2 , $\dots$, 0_2 are driven by the output of the flipflop a_1 , the outputs of the flipflops a_1, b_1 , $\dots$, 0_1 are applied to the above mentioned respective AND-gates in the later portions of the pulse widths of the signals sent out of the terminals a_3, b_3 , $\dots$, g_3 and h_3, i_3 , $\dots$, 0_3 . Therefore, even in the case that a time lag is caused until the output signal of the controlling register R_4 propagates to the above mentioned AND-gate, a positive gate control is made. Further, the memory stage M is to adjust the time when the output signal of the adder Sa is applied to the adder So .

10 25 If random parallel pulse trains are sent out of the output terminals a_3, b_3 , $\dots$ of the controlling register R_4 at a time when driving pulses are applied to the terminals h_4 and a a_4 and the next period is reached, for example, the terminal e_3 will send out the sum of the signal of this terminal itself and the signal of the terminal f_3 in the preceding stage. That is to say, in case the signals of the terminals e_3 and f_3 are respectively 1 and 1 or 0 and 0, a binary zero will be sent out and, in case they are respectively 1 and 0 or 0 and 1, a binary one will be sent out. Thus, each output terminal sends out a binary 0 or 1 with exactly the same probability regardless of its signal in the preceding cycle and therefore the terminals a_3, b_3 , $\dots$, 0_3 send out perfectly random parallel signals in each cycle. As the outputs of the flipflop a_1, b_1 , $\dots$ are gated by these signals, the AND-gates A_a, A_b , $\dots$ also send out random pulses. Though these pulses have a time width three times as large as the time interval of the clock pulses as described above, as the gates A_a, A_b , $\dots$ send out outputs in this sequence, the output pulses of the gates A_a, A_d, A_g , $\dots$, A_b, A_e , $\dots$, A_c, A_f , $\dots$ do not overlap with one another. These pulses are combined respectively at the OR-gates G_{01}, G_{02} and G_{03} and are applied to the AND-gates G_1, G_2 and G_3 as inputs on one side. Also, to these AND-gates G_1, G_2 and G_3 are applied the outputs of the flipflops A, B and C in the initial stage as other inputs. Further, 40 the outputs of the flipflops A, B and C are applied at the trailing edges of the respective outputs sent out of the OR-gates G_{01}, G_{02} and G_{03} . Therefore, the time width of the output pulses of the above mentioned OR-gates will be reduced respectively to one-third and the pulses are combined at the OR-gate G_0 so as not to overlap with one another. Therefore, a random series pulse train is sent out of the output terminal P.

50 As explained above, in the apparatus of this embodiment, pseudo random pulses of a series M sequences are to be sent out and only a few flipflops in the initial stage operate at the clock frequency of said pulse train and the succeeding and the controlling register operate at a speed only less than a fraction of their speed. That is to say, high speed M sequences pulses can be generated by using few expensive high speed components and therefore the apparatus can be manufactured very cheaply. By the way, in the above described embodiment, the ring connected registers are coupled to form only two stages. But multistage ring connected registers coupled can be in greater numbers to further drive other registers in turn by using the outputs of the respective final stages so that the operating speeds of the respective registers may be reduced in turn and the apparatus may be manufactured more easily and cheaply.

55 70 What is claimed is:

1. A pulse pattern generating apparatus comprising pulse means for driving plural ring-connected registers including a

first register having a plurality of successive stages respectively connected to drive separate other ones of said registers in turn, the outputs from the stages of the other driven registers being gated respectively with the outputs of the preceeding driving register stages, said first register being driven with the clock frequency of the pulse pattern.

2. A generator according to claim 1 for generating a random pattern wherein the outputs from the stages of said other registers are connected by electronic switching means to said

gating to receive their output signals, a controlling register having plural stages driven by outputs of said driven registers, and the latter stages delivering signals connected to control said electronic switching means, whereby the outputs of said driven registers are both gated respectively with the outputs of said driving register stages and in addition are randomly switched on and off by said control signals.
